UNITED STATES PATENT OFFICE

2,480,741

RAILWAY CAR CONSTRUCTION

Charles S. Johnston, Glencoe, Ill., assignor to
Transportation Specialties Co., Chicago, Ill., a
corporation of Illinois

Application May 29, 1944, Serial No. 537,778

4 Claims. (Cl. 105—376)

1

This invention relates to railway car constructions and more particularly to the construction of a car end wall and transverse bulkhead supporting beam.

One of the objects of the invention is to provide a railway car end wall formed by a corrugated sheet which is reinforced throughout its width.

Another object of the invention is to provide a corrugated end wall for a railway car which is reinforced by channel members which also form attaching means for connecting an inner insulating wall to the end wall.

A further object of the invention is to provide means for securely anchoring a transverse beam which supports a bulkhead in a refrigerator or like car.

The above and other objects and advantages will be more readily apparent from the following description when read in connection with the accompanying drawing, in which—

Figure 1 is a partial longitudinal section thru a railway car embodying the invention;

Figure 2 is a perspective view with parts broken away and in section of one of the reinforcing members;

Figure 3 is a perspective view of the top reinforcing member;

Figure 4 is a partial perspective view of the transverse beam for supporting the bulkhead; and

Figure 5 is a partial perspective of the floor level reinforcing beam.

The car as shown in Figure 1, comprises the usual bottom 10 supported on longitudinal beams or the like. The end wall of the car is formed by one or more connected corrugated sheets 11 arranged with the corrugations extending horizontally and connected by a bracket 12 to the bottom 10. The car is completed by the usual tops and sides not shown, which may be of standard construction.

According to the present invention the corrugated end wall 11 is reinforced by elongated channel shaped reinforcing strips 13 mounted on the inner side of the end wall with the flanges of the channels extending into and secured as by welding or the like, to the bottoms of the corrugations. The webs of the channels are straight and lie in the plane of the tops of the corrugations.

In the usual car construction, the corrugations are of maximum depth throughout the central portion of the car and taper to flat edges at the sides of the car. In order that the reinforcing

strips may properly follow and reinforce the corrugations throughout their length, the flanges of the strips are tapered adjacent the ends as indicated at 14 in Figure 2 to follow the tapering depth of the corrugations. In this way, the strips reinforce the end sheets substantially from side to side of the car.

On the interior of the end wall an inner insulating wall is provided formed by outer sheathing 15 and inner sheathing 16 between which insulating material 17 is supported. The inner wall is connected to the car end by bolts or like elongated fastenings 18 extending through the inner wall with their heads secured in keyhole slots 19 in the webs of the reinforcing strips. In assembling the inner wall to the car end wall, the bolts may first be placed in the inner wall after which their heads may be slipped through the keyhole openings 19 and moved endwise to lock the bolt heads in place. This construction provides a very simple and highly efficient means of fastening the inner insulating wall to the car end.

At the upper edge of the car end a reinforcing strip 21 of somewhat different construction is preferably employed. As shown, in Figure 3, the strip 21 includes a flange 22 tapered at its ends to fit into the top corrugation and vertical web 23 connected thereto. The edge of the flange 22 may be welded to the end wall at the bottom of the top corrugation and the upper edge of the web 23 may be welded or otherwise secured to the upper flat edge of the car end sheet. Preferably, a series of keyhole openings 24 are provided in the web 23 to receive fastening bolts 25 extending thru the inner wall.

An angle bracket 26 is welded to the inner side of the web 23 extending over the inner wall and having an upwardly extending flange 27 by which it may be secured to an extension of the inner wall and to a top sill 28 of the car.

At the lower end of the end wall a reinforcing member 29 similar to the member 21 is provided to carry bolts 31 extending thru the inner car wall. Supporting plates 32 are secured to the inner surface of the wall by the bolts 31 and pivotally support ice-grates 33 within the car.

Near the lower end of the corrugated end wall a channel shaped beam 34 is provided, welded or otherwise secured to the car end and to the corner 60 of the car. This beam serves to provide additional strength to the car end wall to resist the thrust of a shifting load in the car transmitted thru the bulkhead and thru beams 36 to the car end. The outer ends of flanges of beam 34 are bent angular, and rest on the inner face of the car

end. A series of web plates 34' welded in place in the beam as shown in Figure 5, serve to give added rigidity to the beam.

Adjacent to the end beam 34 is a face plate 40 which is angular in shape and which serves as a backing for the floor pan and an added support for the floor grate support 36. Bolts 35 connect face plate 40 and floor grate supports 36 to the end beam 34. The beams 36 support a floor grate 37 as shown.

The car shown is a refrigerator car which carries a bulkhead 38 for dividing the car into an ice-compartment adjacent one end and a central lading compartment. The bulkhead is preferably movable in the car as more particularly described and claimed in my Patent No. 2,331,197. When in its extended position as shown, the bulkhead is supported in socket members 39 carried by the inner ends of the beams 36. Similar socket members 41 are provided adjacent the end of the car to support the bulkhead when it is in its retracted position.

The beams 36 are supported above the bottom plate 10 by a transverse beam 50 spaced from the end of car and underlying the bulkhead 38. A floor pan 43 extends from the transverse beam to the end of car and has flanged sides and ends turned up to provide a receptacle to catch water coming from the ice compartment above. A floor 44 extends under the lading compartment of car between the transverse beams. A wood beam 42 is fitted beneath the projecting top of transverse beam to form a dam between the space under the ice compartment and the space under the lading compartment.

In order to secure the beams 36 to the transverse beam 50 supporting members 45 are provided connecting to the inner ends of beams 36 under the bulkhead when in its extended position. The supporting members 45 are so formed as to permit air circulation longitudinally of the car therethru. The construction of the transverse beam 50 for securely fastening supporting members 45 to the bottom plate 10 is shown in Figure 4. It consists of a metal strip having a central body portion 46 with one end turned under to form a channel shaped section as indicated at 47. Registering keyhole openings 48 are provided in the central portion 46 and the turned under end 47 of the beam to secure fastening bolts 49 which connect the supporting member 45 to the beam. Stiffening plates 47' are welded in between the central portion 46 and the free end of flange 47 adjacent to the keyhole slots to prevent bending of flange when bolts 49 are tightened. The beam has an angular skirt portion 51 at one side which has secured thereto gusset members 52. The gusset members as shown, are channel shaped in section with angularly cut flanges, the upper portion of which may be welded to the skirt 51 and to the webs of which are bolted the dam beam 42 by means of the bolts 54. Gusset 53 may be placed on dam beam 42 on side opposite from gusset 52. Gussets 52 and 53 are securely fastened to the bottom plate 10 of car. With this construction the beam and the parts supported thereby are fixedly anchored in the car and will not shift under strains to which the car may be subjected.

While one embodiment of the invention has been shown and described in detail it will be understood that this is illustrative only and is not intended as definition of the scope of the invention, reference being had for this purpose to the appended claims.

What is claimed is:

1. A railway car construction comprising an elongated supporting base for the car, a corrugated sheet metal end wall, a bulkhead in the car spaced from the end wall, a transverse beam on the base under the bulkhead, a series of longitudinally extending beams for supporting a floor rack secured at one end to the sheet metal end wall, and means for connecting the other ends of the longitudinal beams to the transverse beam and for supporting the bulkhead thereon including an angular metal plate having gussets secured thereto and to the supporting base of the car.
2. A railway car construction comprising an elongated supporting base for the car, a corrugated sheet metal end wall, a bulkhead in the car spaced from the end wall, a transverse beam on the base under the bulkhead, a series of longitudinally extending beams for supporting a floor rack secured at one end to the sheet metal end wall, and means for connecting the other ends of the longitudinal beams to the transverse beam and for supporting the bulkhead thereon including an angular metal plate having gussets secured thereto and to the supporting base of the car.
- 15 3. A railway car construction comprising an elongated supporting base for the car, a corrugated sheet metal end wall, a bulkhead in the car spaced from the end wall, a transverse beam on the base under the bulkhead, a series of longitudinally extending beams for supporting a floor rack secured at one end to the sheet metal end wall, and means for connecting the other ends of the longitudinal beams to the transverse beam and for supporting the bulkhead thereon including a metal plate doubled back on itself at one edge to form a channel shaped portion with an integral angular flange and gussets secured to the flange and to the supporting base of the car.
- 20 4. A railway car construction comprising an elongated supporting base for the car, a sheet metal end wall connected to the base, a floor in the car above the base, a bulkhead in the car spaced from the end wall, a transverse beam connected to the base under the bulkhead, a reinforcing beam connected to the inner surface of the end wall in line with the floor, the floor being connected to both the transverse beam and the reinforcing beam, and means connecting the bulkhead to the floor and the transverse beam.
- 25 5. A railway car construction comprising an elongated supporting base for the car, a horizontally corrugated sheet metal end wall secured to the base, a floor in the car above the base, a channel shaped reinforcing beam secured to the inner surface of the end wall in line with and connected to the floor, a transverse beam secured to the base and to the floor spaced from the end wall, a bulkhead in the car overlying the transverse beam, and means connecting the bulkhead to the floor and the transverse beam.
- 30 6. A railway car construction comprising an elongated supporting base for the car, a sheet metal end wall connected to the base, a floor in the car above the base, a bulkhead in the car spaced from the end wall, a transverse beam connected to the base under the bulkhead, a reinforcing beam connected to the inner surface of the end wall in line with the floor, the floor being connected to both the transverse beam and the reinforcing beam, and means connecting the bulkhead to the floor and the transverse beam.
- 35 7. A railway car construction comprising an elongated supporting base for the car, a horizontally corrugated sheet metal end wall secured to the base, a floor in the car above the base, a channel shaped reinforcing beam secured to the inner surface of the end wall in line with and connected to the floor, a transverse beam secured to the base and to the floor spaced from the end wall, a bulkhead in the car overlying the transverse beam, and means connecting the bulkhead to the floor and the transverse beam.
- 40 8. A railway car construction comprising an elongated supporting base for the car, a horizontally corrugated sheet metal end wall secured to the base, a floor in the car above the base, a channel shaped reinforcing beam secured to the inner surface of the end wall in line with and connected to the floor, a transverse beam secured to the base and to the floor spaced from the end wall, a bulkhead in the car overlying the transverse beam, and means connecting the bulkhead to the floor and the transverse beam.
- 45 9. A railway car construction comprising an elongated supporting base for the car, a horizontally corrugated sheet metal end wall secured to the base, a floor in the car above the base, a channel shaped reinforcing beam secured to the inner surface of the end wall in line with and connected to the floor, a transverse beam secured to the base and to the floor spaced from the end wall, a bulkhead in the car overlying the transverse beam, and means connecting the bulkhead to the floor and the transverse beam.
- 50 10. A railway car construction comprising an elongated supporting base for the car, a horizontally corrugated sheet metal end wall secured to the base, a floor in the car above the base, a channel shaped reinforcing beam secured to the inner surface of the end wall in line with and connected to the floor, a transverse beam secured to the base and to the floor spaced from the end wall, a bulkhead in the car overlying the transverse beam, and means connecting the bulkhead to the floor and the transverse beam.
